DRUM

Einar Ronne, Copenhagen, Denmark, assignor to
 F. L. Smith & Co., New York, N. Y., a corporation of New Jersey

Application July 25, 1946, Serial No. 686,258
 In Denmark December 22, 1944

Section 1, Public Law 690, August 8, 1946
 Patent expires December 22, 1964

8 Claims. (Cl. 259—3)

1

This invention relates to apparatus for the treatment of solids and slurries with gases for the purpose of effecting heat exchange or causing chemical changes. More particularly, the invention is concerned with a novel rotary drum for the purpose mentioned which is constructed to provide a plurality of lengthwise passages defined by partition means which serve the additional purpose of stiffening the drum shell and preventing its deformation under load. By the use of the partition means for stiffening purposes, it is possible to make the drum of relatively thin metal stock, so that the weight of the drum is greatly reduced and it is less expensive to build.

The drum of the invention may be used for the heating of materials in pulverulent, nodular, or slurry form, as in the preliminary heating operations in the production of cement, for drying coal, lignite, peat, etc., and for other purposes. As it may be employed to advantage when mounted in overhanging relation at the intake end of a rotary cement kiln for preheating of the cement raw materials, an embodiment of the invention in that form will be illustrated and described for purposes of explanation.

At the present time, drums having internal partitions and used for heating materials are made in large sizes, and, when such a drum is mounted in overhanging position, the drum is subjected to strong forces tending to deform it and resulting from the weight of the drum, partitions, and load. In order to restrict the deformation of the drum within suitable limits, it has been the practice to make the drum of plate stock sufficiently heavy to give the drum the desired rigidity, although one or more outside rings are often used to stiffen the drum. The partitions within the drum serve to improve the heat exchange but do not contribute toward the rigidity of the drum or its resistance to deformation. Because of its great weight, such a drum is expensive to construct.

The present invention is directed to the provision of a rotary drum for the purposes above described, which is much lighter in weight than prior drums and is thus less expensive to construct and to operate. In the new drum, the required rigidity is not provided entirely by the drum wall as in prior constructions, but, instead,

2

the drum has internal partitions which are so constructed as to stiffen and support the drum wall. A central rigid body, which may be a tube of small diameter relative to the drum and extending axially of the latter, is mounted within the drum and the walls forming the partitions radiate from the tube. In addition, arcuate partitions extend between the radial partitions and the construction is such that the partitions are subjected to tensile stresses and may, accordingly, be of relatively light weight.

For a better understanding of the invention, reference may be had to the accompanying drawings, in which:

15 Fig. 1 discloses a drum constructed in accordance with the invention mounted in overhanging relation at the end of a rotary kiln;

Fig. 2 is a diagrammatic sectional view on the line 2—2 of Fig. 1;

20 Fig. 3 is a sectional perspective view on the line 3—3 of Fig. 1;

Figs. 4 and 5 are sectional views on the lines 4—4 and 5—5, respectively, of Fig. 1; and

Fig. 6 is a fragmentary transverse sectional view of a modified construction.

25 The apparatus illustrated in Fig. 1 includes a rotary kiln 10 of conventional construction which comprises a shell 11 with the usual lining 12. A tire 13 encircles the shell near one end and runs on rollers 14 or slide shoes. At its intake end, the kiln is formed with an outwardly directed radial flange 15, against one face of which are mounted supporting members 16 for the drum 17.

30 The drum includes a shell of relatively light stock, which extends over the edge of flange 15 and is secured by suitable means to the members 16. At its free end, the shell has a conical section 18, which extends to an intake section 19 of a diameter substantially less than that of the shell.

35 A rigid tube 20 of relatively heavy stock extends axially through the main part of the shell and the end of the tube facing the intake section of the drum is closed by a plate 21. A plurality of imperforate partitions 22 extend radially from the outer surface of the tube to the inner wall of shell 17.

40 Between the tube and the shell 17 are arcuate partition members 23, 24, arranged in two series to form inner and outer concentric cylindrical partitions. Each partition member 23 extends 45 between and is connected to a pair of adjacent

radial partitions 22, and a radial partition 25 extends outwardly from the median line of the outer surface of each arcuate partition member 23 to the inner surface of the shell 17. Each arcuate partition member 24 extends from one of the radial partitions 22 to one of the radial partitions 25.

The various partition members may be secured in place in any desired manner, as, for example, angle irons 26 may be secured in pairs to the outer surface of tube 20 by bolting, riveting, or welding, and the inner edge of each partition member 22 may be received between a pair of such angle irons and rigidly secured in place. The outer edge of each partition 22 may be secured in the same manner to the inner surface of shell 17. The arcuate partition members 23 may have edge flanges 23a secured to partitions 22, and the arcuate partition members 24 may have similar flanges 24a secured to partitions 22 and 25. The partitions 25 are then secured between pairs of angle irons 27 and 28 attached, respectively, to the outer surfaces of partition members 23 and the inner wall of the shell 17. In sections of the shell which become highly heated, the edges of partitions lying between pairs of angle irons are not rigidly attached to the latter, so that relative expansion of the parts is permitted.

At their intake ends, the arcuate partition members 23, 24 are provided with radial flanges 29, and a flight section 30 is mounted on the concave surface of each arcuate partition member inward from the flange. Each of the radial partitions 22, 25 is provided with an extension 31 beyond the flanges 29 and the extension is formed with a lateral flange 32 which terminates in a portion 32a extending along the inner surface of shell 17 and having the form of a section of a flight. With this construction, material introduced into the shell through the intake section 19 slides down the interior of the conical section 18 to land upon the inner surface of the main section of the shell in front of the flight sections 32a. As the shell rotates, the material is guided by the flight sections to the extensions 31 and moves radially inwardly along those extensions to be discharged in the passages. Within each passage, the material is prevented from backing up by the flight section 30.

At the outlet end of the shell, the arcuate partition members 23, 24 extend beyond the radial partitions and the extensions are provided with inward radial flanges 33 and have spaced openings from which discharge spouts 34 extend radially outwardly. The spouts from the extensions from the arcuate partition members 23 lead to the inner surfaces of the extensions from the arcuate partition members 24, and the spouts from the extensions from the members 24 discharge upon the inner surface of the shell. A plurality of scoops 35 are mounted within the shell along the flange 15 and, as the shell rotates, material discharged from the spouts is picked up by the scoops and discharged into the interior of the kiln.

With the construction described, the light partitions together with the rigid central tube 20 impart such rigidity to the shell that it may be made of relatively light stock and, while the tube 20 is thick-walled, its weight is not comparable with the saving in weight resulting from the use of light material for the shell. The complete drum structure is, accordingly, much lighter in weight than prior similar drums.

I claim:

1. A drum for use in the treatment of solids and slurries with gases which comprises a cylindrical shell, a rigid member within the shell and extending coaxially thereof, a set of angularly spaced radial plates extending between the outside of the member and the inner surface of the shell, an inner continuous series of arcuate plates connecting the radial plates and together forming an inner cylindrical partition enclosing and spaced from the member, a second set of radial plates extending from the inner surface of the shell to the outer surface of respective arcuate plates only, and an outer continuous series of arcuate plates connecting the radial plates of the two sets and forming an outer cylindrical partition lying between the shell and the first partition, the arcuate and radial plates extending lengthwise of the drum and terminating short of the ends thereof and the spaces between the member and the inner partition, between the partitions, and between the outer partition and the shell being divided by the radial plates into three concentric series of passages extending lengthwise of the drum and open at both ends, the material to be treated and the gases traveling through the passages as the drum is rotated on its longitudinal axis.

2. A drum for use in the treatment of solids and slurries with gases which comprises a cylindrical shell, a rigid member within the shell and extending coaxially thereof, a set of angularly spaced radial plates extending between the outside of the member and the inner surface of the shell, an inner continuous series of arcuate plates connecting the radial plates and together forming an inner cylindrical partition enclosing and spaced from the member, a second set of radial plates extending from the inner surface of the shell to the outer surface of respective arcuate plates only, an outer continuous series of arcuate plates connecting the radial plates of the two sets and forming an outer cylindrical partition lying between the shell and the first partition, the arcuate and radial plates extending lengthwise of the drum and terminating short of the ends thereof and the spaces between the member and the inner partition, between the partitions, and between the outer partition and the shell being divided by the radial plates into three concentric series of passages extending lengthwise of the drum and open at both ends, the material to be treated and the gases traveling through the passages as the drum is rotated on its longitudinal axis, and scoops mounted on the ends of the radial plates at one end of the drum, the scoops having intake ends adjacent the shell and leading to the respective passages.

3. A drum for use in the treatment of solids and slurries with gases which comprises a cylindrical shell, a rigid member within the shell and extending coaxially thereof, a set of angularly spaced radial plates extending between the outside of the member and the inner surface of the shell, an inner series of arcuate plates connecting the radial plates and together forming a cylindrical partition enclosing and spaced from the member, a second set of radial plates extending from the inner surface of the shell to the outer surface of respective arcuate plates only, an outer series of arcuate plates connecting the radial plates of the two sets and forming a cylindrical partition lying between the shell and the first partition, the radial plates subdividing the spaces between the member and the first partition, be-

tween the partitions, and between the second partition and the shell into a plurality of passages, which are open at both ends and through which the material to be treated and the gases travel as the drum is rotated on its longitudinal axis, radial flanges mounted on the ends of the cylindrical partitions at one end of the drum, openings through each partition adjacent the flange thereon, and spouts attached to the outer sides of the partitions and leading from the openings.

4. A drum for use in the treatment of solids and slurries with gases which comprises a cylindrical shell, a rigid member within the shell and extending coaxially thereof, a set of angularly spaced radial plates extending between the outside of the member and the inner surface of the shell, an inner series of arcuate plates connecting the radial plates and together forming a cylindrical partition enclosing and spaced from the member, a second set of radial plates extending from the inner surface of the shell to the outer surface of respective arcuate plates only, an outer series of arcuate plates connecting the radial plates of the two sets and forming a cylindrical partition lying between the shell and the first partition, the radial plates subdividing the spaces between the member and the first partition, between the partitions, and between the second partition and the shell into a plurality of passages, which are open at both ends and through which the material to be treated and the gases travel as the drum is rotated on its longitudinal axis, radial flanges mounted on the ends of the cylindrical partitions at one end of the drum, openings through each partition adjacent the flange thereon, and spouts attached to the outer sides of the partitions and leading from the openings, the spouts from the inner partition discharging on the outer partition inward from its flange and the spouts from the outer partition terminating short of the inner surface of the shell.

5. A drum for use in the treatment of solids and slurries with gases which comprises a cylindrical shell, a rigid tube within the shell and extending coaxially thereof, the tube being blocked, a set of angularly spaced radial plates extending between the outside of the member and the inner surface of the shell, an inner continuous series of arcuate plates connecting the radial plates and together forming an inner cylindrical partition enclosing and spaced from the member, a second set of radial plates extending from the inner surface of the shell to the outer surface of respective arcuate plates only, and an outer continuous series of arcuate plates connecting the radial plates of the two sets and forming an outer cylindrical partition lying between the shell and the first partition, the arcuate and radial plates extending lengthwise of the drum and terminating short of the ends thereof and the spaces between the member and the inner partition, between the partitions, and between the outer partition and the shell being divided by the radial plates into three concentric series of passages extending lengthwise of the drum and open at both ends, the material to be treated and the gases traveling through the passages as the drum is rotated on its longitudinal axis.

6. A drum for use in the treatment of solids and slurries with gases which comprises a cylindrical shell, a rigid member within the shell and extending coaxially thereof, a set of angularly spaced radial plates extending between the outside of the member and the inner surface of the

shell, an inner series of arcuate plates connecting the radial plates and together forming a cylindrical partition enclosing and spaced from the member, a second set of radial plates extending from the inner surface of the shell to the outer surface of respective arcuate plates only, an outer series of arcuate plates connecting the radial plates of the two sets and forming a cylindrical partition lying between the shell and the first partition, the radial plates subdividing the spaces between the member and the first partition, between the partitions, and between the second partition and the shell into a plurality of passages, which are open at both ends and through which the material to be treated and the gases travel as the drum is rotated on its longitudinal axis, the radial plates extending beyond the arcuate plates at one end of the drum, flanges along the projecting edges of the radial plates, and helically directed plates connected to the outer edges of the flanges extending along the inner surface of the shell.

7. A drum for use in the treatment of solids and slurries with gases which comprises a cylindrical shell, a rigid member within the shell and extending coaxially thereof, a set of angularly spaced radial plates extending between the outside of the member and the inner surface of the shell, means on the outer surface of the member and the inner surface of the shell for confining said plates against angular displacement relative to the shell and member while permitting edge-wise movements of the plates, an inner continuous series of arcuate plates connecting the radial plates and together forming an inner cylindrical partition enclosing and spaced from the member, a second set of radial plates extending from the inner surface of the shell to the outer continuous surface of respective arcuate plates only, and an outer series of arcuate plates connecting the radial plates of the two sets and forming an outer cylindrical partition lying between the shell and the first partition, the arcuate and radial plates extending lengthwise of the drum and terminating short of the ends thereof and the spaces between the member and the inner partition, between the partitions, and between the outer partition and the shell being divided by the radial plates into three concentric series of passages extending lengthwise of the drum and open at both ends, the material to be treated and the gases traveling through the passages as the drum is rotated on its longitudinal axis.

8. A drum for use in the treatment of solids and slurries with gases which comprises a cylindrical shell, a rigid member within the shell and extending coaxially thereof, a set of angularly spaced radial plates extending between the outside of the member and the inner surface of the shell, a plurality of series of arcuate plates connecting the radial plates and together forming cylindrical partitions concentric with and enclosing and spaced from the member, and other radial plates extending from the inner surface of the shell inwardly to the outer surfaces of certain of said arcuate plates and lying between the radial plates of said set, the arcuate and radial plates extending lengthwise of the drum and terminating short of the ends thereof, and said arcuate and radial plates dividing the space within the drum between the shell and said member into a plurality of concentric series of passages extending lengthwise of the drum and open at both ends, the material to be treated and the

gases traveling through the passages as the drum rotates on its longitudinal axis.
